VANITY CASE

Filed April 18, 1929

UNITED STATES PATENT OFFICE

ALBERT HAGEL, OF BLOOMFIELD, NEW JERSEY, ASSIGNOR TO CONSOLIDATED SAFETY PIN CO., OF BLOOMFIELD, NEW JERSEY, A CORPORATION

VANITY CASE

Application filed April 13, 1929. Serial No. 356,067.

My invention relates to an improvement in cigarette compacts, the current term employed to designate combined cigarette cases and vanity boxes as made and sold for the use of women, the object being to produce an article of the character described combining compactness and elegance of form with particular convenience in use.

With these ends in view, my invention consists in a cigarette compact having certain details of construction and combinations of parts as will be hereinafter described and particularly recited in the claims.

In the accompanying drawings:

Fig. 1 is a plan view of my improved cigarette compact;

Fig. 2 is an edge view thereof;

Fig. 3 is a view thereof on actual scale, shown as open;

Fig. 4 is a perspective view thereof, shown as open, with the mirror lifted into position for use;

Fig. 5 is an enlarged scale view in transverse section on the line 5—5 of Fig. 1; and

Fig. 6 is a detached perspective view of the pivotal cigarette-retainer.

In carrying out my invention as herein shown, I employ a struck-up sheet-metal compact-body 10 and a complementary struck-up sheet-metal compact-cover 11, the said body and cover having straight sides and rounded ends, and their main portions or bodies being agreeably bulged or contoured to increase their capacity and enhance their appearance, as well as their feeling in the hand. It is designed that in making my improved cigarette compact the said body and cover shall be lacquered or enameled to match milady's costume or features of it. The said body and cover are secured together by a hinge 12 of any approved construction, the body being furnished with a spring-fastener 13 of any approved construction engaging 40 with a fastening-bar 14 produced by cutting

and striking up the cover at a corresponding point in the adjacent edge thereof.

The said compact-cover 11 is adapted in length and depth for the reception of a number of cigarettes 15 normally held in place by a transversely-arranged pivotal retainer 16 having a centrally-arranged finger-piece 17 and provided at its respective ends with corresponding arms 18 by means of which it is secured by pivots 19 to the inner faces of the sides of the cover. The said retainer presses upon the cigarettes when in its normal position, as shown in Figs. 3, 4 and 5, to hold them in place and clears them sufficiently when lifted into its open position to permit them to be individually inserted or removed, as the case may be.

The compact-body 10 receives a flat mounting-plate 20 having straight sides and rounded ends and just enough smaller in external dimensions than the internal dimensions of the compact-body to fit snugly therewith, as shown in Fig. 5, in which the flange 21 of the plate is shown as frictionally engaged with the inner surfaces of the straight side walls and rounded ends of the compact-body. The central portion of the said plate 20 is struck inward to produce a flat border 22 located in the plane of the compact and a recess or rabbet 23 for the reception of a mirror-unit consisting of a sheet-metal mirror-frame 24 carrying a mirror 25. The lower reach of the recess 23 provides a horizontal shoulder for the said mirror-unit to rest upon when the same is in its closed position. The lower edge of the mirror-frame 24 is secured by hinges 26 of any approved design to the upper reach of the flat border 22, these hinges being received when the compact is closed, within the upper end of the interior cigarette-receiving chamber formed by the compact-cover 11. When in its closed position the back of the mirror-frame 24 lies in the plane (Fig. 5) of the flat border 22 of the mounting-plate.

Within the mirror-supporting shoulder aforesaid of the mounting-plate, the same is struck downward by the depth of a step 27 to produce a clearance-space 28 between the face 25 of the mirror when the same is in its closed position and the face of the depressed main body of the mounting-plate 20 which lies in a plane parallel therewith, the said clearance-space receiving the powder and rouge puffs, which are not shown but which will rest respectively upon a compact of powder and a compact of rouge contained in a flanged circular powder-container or cup 29 and a corresponding but smaller rouge-container or cup 30 set into circular openings 31 and 32 in the depressed flat main central portion of the plate. The clearance-space 28 aforesaid also provides clearance for a lip-stick which is not shown but which will be located in a recess 33 formed by cutting the mounting-plate and bending the cut portions thereof so as to form end-walls 34 and inwardly-curved side-flanges 35 for the retention of the lip-stick in place.

Under my improved construction as described the mirror-unit is interposed between the cigarettes in the compact-cover 11 and the toilet accessories in the compact-body 10, while abundant space is provided between the face of the mirror and the central portion of the mounting-plate for the toilet accessories installed in the latter.

I claim:

1. In a compact, the combination with an oblong sheet-metal compact-body struck up to form a receiving-chamber, of a complementary oblong sheet-metal compact-cover struck up to form a receiving-chamber, a hinge uniting the said compact-body and compact-cover by their adjacent side edges, fastening-means for holding them closed, retaining-means located within the said cover, an oblong mounting-frame fitting within the said chambered body, struck inward for the formation of a rabbet, stepped below the said rabbet to produce a clearance-space and formed below the said clearance-space with openings for the reception of cosmetic-containers, and a mirror-unit hinged by its lower edge to the upper edge of the said mounting-frame upon the rabbet of which it rests when in its closed position, so that the back of the frame will be in the plane of the mounting-frame.

2. In a compact, the combination with an oblong chambered compact-body, of a complementary oblong chambered compact-cover, the said body and cover being hinged together by their adjacent side edges, fastening-means for holding them closed, retaining-means located within the chambered compact-cover, an oblong mounting-frame fitting within the chamber of the compact-body and struck up to form a supporting-shoulder, and also struck up to form a clearance-space below the

said shoulder and adapted to receive cosmetic-containers in a plane below the said clearance-space, and an oblong mirror-unit hinged by its lower edge to the upper edge of the said oblong mounting-frame, resting when in its closed position upon the supporting-shoulder thereof, and isolated by the said clearance-space from the cosmetics in the cosmetic-containers in the lowest plane of the said frame.

In testimony whereof, I have signed this specification.

ALBERT HAGEL.
